BRIGHTENING AGENTS

Franz Marschall and Harlan B. Freyermuth, Easton, Pa., and William W. Williams, New York, N.Y., assignors to General Aniline & Film Corporation, New York, N.Y., a corporation of Delaware
No Drawing. Filed Apr. 4, 1956, Ser. No. 575,925
3 Claims. (Cl. 260—240)

This invention relates to novel bistriazole compounds possessing new and useful properties which render them particularly useful as fluorescing optical bleaching or whitening agents.

It is well known that textiles tend to develop a yellowish shade on aging which cannot be removed by ordinary methods of bleaching or washing. The heretofore used methods of "bluing" white materials with blue pigments or fugitive blue dyestuffs have become quite obsolete in modern laundry practice and have been largely superseded by methods employing fluorescent optical bleaching agents or brighteners as additives to the soap or detergent in the washing bath. These brightening agents are usually conveniently supplied commercially in the form of intimate admixtures with the soap or detergent in bars, flakes, powders, etc. The fluorescent optical bleaching agents perform their desired function by virtue of their characteristic absorption of ultra-radiations and subsequent conversion of this energy to light energy within the visible spectrum. This converted and emitted light energy tends to neutralize any yellowness of the material and thereby increase the apparent whiteness thereof.

Compounds which have been suggested and employed as fluorescent brightening agents include the following:

I. Acylated derivatives of 4,4'-diamino-stilbene-2,2'-disulfonic acid.

II. Acylated derivatives of 4,4'-diamino-diphenyl-2,2'-disulfonic acid.

III. Triazyl derivatives of diamino stilbene disulfonic acid.

IV. Triazyl derivatives of diamino diphenyl disulfonic acid.

V. Acylated derivatives of diamino dibenzothiophene dioxide, etc.

Compounds of the Types I and II are disclosed in U.S. Patents 2,581,059 and 2,643,198 and in British Patent 584,484.

Compounds of the Types III and IV are disclosed in U.S. Patent 2,618,636 and in application Serial No. 381,856 published May 11, 1943, now U.S. Patent 2,926,259, by the A.P.C.

Compounds of Type V are exemplified in U.S. Patents 2,563,493 and 2,563,795.

In addition to the five types mentioned above, other triazyl compounds have been suggested. Thus U.S. Patent 2,668,777 discloses a bistriazole of the formula:

and U.S. Patent 2,666,062 discloses a compound having the formula:

There are other known compounds containing both stilbene and triazole moieties but such compounds are not brightening agents for the purposes herein contemplated but rather are yellow dyes.

5 The compounds of the present invention are 4-(2-substituted-7-benzo[1,2,3,4]bistriazole) stilbenes devoid of chromophoric groups and have the following general formula:

10

15

20

25

30

35

40

45

50

55

wherein B represents a benzene nucleus which may contain a substituent such as hydrogen, halogen, such as chlorine, bromine and the like, alkyl such as methyl, ethyl, propyl and the like, alkoxy such as methoxy, ethoxy, n-propoxy, n-butoxy and the like, B' represents a benzene nucleus which contains a substituent such as

and the like,

or sulfo (SO3H, SO3Na, SO3K and the like) in the 2-position; wherein R is the residue of a diazotizable aryl amine or amino heterocyclic compound, and when B' has a sulfonamido substituent in the 2-position, R must contain a sulfo radical (e.g., SO3H, SO3Na, SO3K and the like).

The novel compounds of this invention are characterized by having excellent fiber substantivity, an aesthetically desirable hue as contrasted with an aesthetically undesirable green hue of some of the prior art brightening agents, a greater apparent whiteness than prior art compounds, outstanding resistance to bleaching agents commonly used in laundering processes, and excellent light-fastness. As a result of these remarkable properties fabrics washed with soaps or other detergents containing small amounts of the novel compounds of this invention usually in the form of the sodium or other alkali metal salt become much brighter in the case of colors and whiter for others than fabrics which are washed either in the absence of such brightening agents or in the presence of the previously known brightening agents.

The compounds of this invention may also be incorporated in synthetic fibers and fabrics particularly during the manufacture thereof and especially in those of cellulose origin such as regenerated cellulose, cuprammonium cellulose, cellulose acetate and the like, by adding a small amount of the brightening agent to the spinning solutions or precipitating baths in order to achieve a

noticeable increase in the whiteness of the finished product. These brighteners may also be used to effect a whitening of paper by the impregnation thereof (with the selected brightening agent) or by the incorporation of the brightening agent in the paper making pulp prior to the final drying thereof. Additionally, the brightening agents of this invention may be employed to effect a whitening of waxes, gums and the like by adding small amounts of the agent to such substances.

The bistriazoles of this invention are prepared by coupling a 4-diazostilbene with a couplable 2-aryl-5-amino-2,1,3-benzotriazole or 2-hetero-5-amino-2,1,3-benzotriazole and then oxidizing the resultant product to form a bistriazole in accordance with the following equation:

wherein R represents the groupings given above for (I) and Y is halogen (e.g., chlorine). The 4-diazostilbene compounds (II) useful in this invention include the following:

2-sulfo (or substituted sulfonamido) diazostilbenes:
 2-sulfo-4-diazostilbene
 2-chloro-2'-sulfo-4'-diazostilbene
 3-chloro-2'-sulfo-4'-diazostilbene
 4-chloro-2'-sulfo-4'-diazostilbene
 2-bromo-2'-sulfo-4'-diazostilbene
 3-bromo-2'-sulfo-4'-diazostilbene
 4-bromo-2'-sulfo-4'-diazostilbene
 2-methoxy-2'-sulfo-4'-diazostilbene
 3-methoxy-2'-sulfo-4'-diazostilbene
 4-methoxy-2'-sulfo-4'-diazostilbene
 2-methyl-2'-sulfo-4'-diazostilbene
 3-methyl-2'-sulfo-4'-diazostilbene
 4-methyl-2'-sulfo-4'-diazostilbene
 2-(N,N-dimethyl-sulfonamido)-4-diazostilbene
 2-(N,N-diethyl-sulfonamido)-4-diazostilbene
 2-(N,N-bishydroxyethyl-sulfonamido)-4-diazostilbene
 2-(N,N-diethyl-sulfonamido)-4'-methoxy-4-diazostilbene

The triazoles (III) operable in this invention are prepared in general by the oxidation of the product formed by coupling an organic diazo compound with m-phenylenediamine. The triazoles (III), above, and the bistriazoles (I) of this invention, as heretofore described, are prepared, after coupling to form the azo compound, by an oxidation step which results in the conversion of an ortho, primary amino group to a hetero atom of a triazole ring. The procedure for this oxidation may vary depending upon the choice of the oxidizing agent. For example, when one uses ammoniacal (or other organic base, e.g., pyridine, etc.) copper sulfate as the oxidizing agent, the resultant by-products of such reagent may be removed by adjustment of the pH of the solution, i.e., the reduction products of the oxidizing agents may be solubilized by making the solution more acidic, so that the by-products are removed in the filtrate by a filtration step. Alternatively, the by-products may be removed in the filtrate by making the reaction medium alkaline with ammonia (pH 11) prior to filtration. While it is preferred to use metallic (ic-ous) oxidizing agents such as copper sulfate, ferric chloride, ferric NH_4SO_4 , etc., one may also employ hydrogen peroxide, KMnO_4 , $\text{K}_2\text{Cr}_2\text{O}_7$, CaOCl_2 , NaOCl , Na perborate, oxygen, etc.

In preparing the various azo intermediates for the desired triazoles (I) and (III), the diamino containing coupling component in dilute aqueous solution or suspension is treated with a solution of a diazotized amine. In the case of compounds (III) the diazotized amines used are those represented by the R residue as given in Formulas I and III. Suitable amines as precursors for these diazotized compounds include:

aniline
 p-Sulfanilic acid
 sulfanilamide
 β -Naphthylamine
 amino pyridines, e.g.
 β -Amino pyridines such as

3-amino pyridine
 3-amino-2-methoxy pyridine
 3-amino-5-bromo pyridine
 3-amino-2-chloro pyridine
 5-amino-2-chloro pyridine

5
 o-Anisidine
 m-Anisidine
 p-Anisidine
 amino carbazoles, e.g.
 10 1-amino carbazole
 2-amino carbazole
 3-amino carbazole
 1-amino-6-methoxy carbazole
 2-amino-4-methoxy carbazole
 15 1-amino-3,4-dibromo carbazole
 aminobenzothiophenes, e.g.
 4-thianaphthenamine
 5-thianaphthenamine
 4-bromo-5-thianaphthenamine

20 In the case of the compounds of this invention (I) the diazotized amines (II) may be derived from the corresponding aromatic amino stilbenes described above.

The pH of the coupling reaction media may be varied according to the coupling component used. For example, in the coupling reaction involving the formation of the compounds of this invention (I) a pH of about 4 to 5 is preferred, although a pH as high as about 6.5 may be suitably employed to effect the desired azo coupling reaction. The couplings are preferably carried out in aqueous medium employing sodium acetate and acetic acid as buffers although other means of maintaining the desired acidity may be employed. One may also employ pyridine as a coupling assistant in the manner well known in the azo coupling art. Similar conditions and pH ranges are used in the preparation of those intermediate azo compounds which are the precursors for the triazoles (III).

The bistriazoles of this invention after the oxidation step may be recovered in the form of a paste by the filtration of the oxidation mixture and may be used in this form or dried to a powder. If desired, the bistriazoles may be purified by crystallization from a solvent, for example:

45 pyridine
 picoline
 formamide
 acetamide
 dimethyl formamide
 50 acetic acid, and the like.

Among the 2-aryl-5-amino-2,1,3-benzotriazoles and 2-hetero-5-amino-2,1,3-benzotriazoles (III) which may be used as couplers or coupling components with the diazostilbene compounds (II) given above are the following:

2-phenyl-5-aminobenzotriazole
 2-naphthyl-5-aminobenzotriazole
 2-(2'-pyridyl)-5-aminobenzotriazole
 60 2-(3'-pyridyl)-5-aminobenzotriazole
 2-(4'-pyridyl)-5-aminobenzotriazole
 2-lutidyl-5-aminobenzotriazole
 5-aminobenzotriazolyl benzene o-sulfonic acid
 5-aminobenzotriazolyl benzene m-sulfonic acid
 5-aminobenzotriazolyl benzene p-sulfonic acid
 65 1-(5-aminobenzotriazolyl)naphthylamine-4-sulfonic acid
 1-(5-aminobenzotriazolyl)naphthylamine-5-sulfonic acid
 1-(5-aminobenzotriazolyl)naphthylamine-6-sulfonic acid
 70 1-(5-aminobenzotriazolyl)naphthylamine-7-sulfonic acid
 1-(5-aminobenzotriazolyl)naphthylamine-8-sulfonic acid
 2-(5-aminobenzotriazolyl)naphthylamine-5-sulfonic acid
 75

- 2-(5-aminobenzotriazolyl)naphthylamine-6-sulfonic acid
 2-(5-aminobenzotriazolyl)naphthylamine-7-sulfonic acid
 2-(5-aminobenzotriazolyl)naphthylamine-8-sulfonic acid and the corresponding sulfonamides
 2(o-methoxyphenyl)-5-aminobenzotriazole
 2(m-methoxyphenyl)-5-aminobenzotriazole
 2(p-methoxyphenyl)-5-aminobenzotriazole
 2-(2-[1-chloro]naphthyl)-5-aminobenzotriazole
 2-(2-[3-chloro]naphthyl)-5-aminobenzotriazole
 2-(2-[4-chloro]naphthyl)-5-aminobenzotriazole
 2-(2-[5-chloro]naphthyl)-5-aminobenzotriazole
 2-(2-[6-chloro]naphthyl)-5-aminobenzotriazole
 2-(2-[7-chloro]naphthyl)-5-aminobenzotriazole
 2-(2-[8-chloro]naphthyl)-5-aminobenzotriazole
 2-(acetamidophenyl)-5-aminobenzotriazole
 2-(benzamidophenyl)-5-aminobenzotriazole
 2-(5-[acetamidonaphthyl])-5-aminobenzotriazole
 2-(m-trifluoromethyl)phenyl-5-aminobenzotriazole
 2-(4-carbalkoxyphenyl)-5-aminobenzotriazole

- 2-(carbamidophenyl)-5-aminobenzotriazole
 2-(o-acetophenyl)-5-aminobenzotriazole
 2-(m-acetophenyl)-5-aminobenzotriazole
 2-(p-acetophenyl)-5-aminobenzotriazole
 2-(o-benzoylphenyl)-5-aminobenzotriazole
 2-(m-benzoylphenyl)-5-aminobenzotriazole
 2-(p-benzoylphenyl)-5-aminobenzotriazole and the like

The following examples in which the parts are by weight unless otherwise indicated are illustrative of the instant invention and are not to be regarded as limitative thereof.

Example 1

6.9 parts of 4-amino-2-stilbenesulfonic acid is dissolved in 100 parts water and 8 parts of 40% sodium hydroxide solution. The solution is cooled to 0-5° C. and 17.9 parts concentrated hydrochloric acid (specific gravity 1.19) is added. The fine suspension of the aminostilbenesulfonic acid is diazotized by the addition of a solution of 1.8 parts sodium nitrite in 20 parts water during one and one-half hours at 0-5° C. The excess nitrous acid is destroyed by the addition of 4 parts of 10% sulfamic acid solution. The diazo solution is added rapidly to a solution of 7.3 parts 2-(4'-sulfonamido-phenyl)-5-amino-2,1,3-benzotriazole (prepared by coupling diazotized sulfanilamide to meta-phenylenediamine at a pH of 5 and oxidizing the azo dye formed to the corresponding benzotriazole) and 343 parts pyridine and 50 parts water. After coupling is finished, the azo dye mixture is acidified with 416 parts concentrated hydrochloric acid, filtered and the wet cake heated with 196 parts pyridine and 25 parts cupric sulfate ($CuSO_4 \cdot 5H_2O$) previously dissolved in 200 parts of water to 90-95° C. for 16 hours. Upon cooling, the product is filtered and dried in a vacuum oven at 70-75° C.

Example 2

- 13.8 parts of 4-amino-2-stilbenesulfonic acid is dissolved in 200 parts water and 10 parts of 40% sodium hydroxide solution. The solution is cooled to 0° C. and acidified with 27.3 parts concentrated hydrochloric acid (specific gravity 1.19). The suspension of aminostilbenesulfonic acid is diazotized by adding a solution of 3.5 parts sodium nitrite in 25 parts water at 0° C. during one and one-half hours. The slight excess of nitrous acid is destroyed by the addition of 6 parts 10% sulfamic acid. The diazo solution is added to a solution of 10.5 parts 2-phenyl-5-amino-2,1,3-benzotriazole and 262 parts glacial acetic acid. 200 parts of 30% sodium acetate solution is added to raise the pH to 4-5 and the mixture is stirred for 12 hours. After the coupling is finished the azo dye is filtered and washed with water. The wet presscake is slurried with 196 parts pyridine. A solution of 25 parts cupric sulfate ($CuSO_4 \cdot 5H_2O$) and 200 parts water is added and the mixture is heated to reflux for 12 hours. The reaction mixture is cooled to 10-15° C., filtered and washed. The triazole product is dried in a vacuum oven at 70-75° C.

Example 3

- 30 13.8 parts 4-amino-2-stilbenesulfonic acid are dissolved in 200 parts water and 10 parts 40% sodium hydroxide solution. The solution is cooled to 0° C. and 17.9 parts concentrated hydrochloric acid are added. The suspension of the aminostilbenesulfonic acid is diazotized with a solution of 3.5 parts sodium nitrite and 25 parts water during one and one-half hours at 0° C. The excess nitrous acid is decomposed by the addition of 5.5 parts of a 10% sulfamic acid solution. The diazo solution is added to a solution of 14.5 parts 2-(4'-sulfonylphenyl)-5-amino-2,1,3-benzotriazole (prepared by coupling diazotized sulfanilic acid to meta-phenylenediamine

40

- and oxidizing the azo dye formed to the corresponding triazole with an ammoniacal cupric sulfate solution), 2000 parts water and 10 parts 40% sodium hydroxide solution. 250 parts of 30% sodium acetate solution are added to raise the pH to 4-5 and the mixture is stirred for 12 hours. After the coupling is finished, 150 parts common salt are added and the mixture is cooled to 20° C. The azo dye is filtered, pressed as dry as possible and the cake is slurried with 245 parts pyridine. 42 parts cupric sulfate ($CuSO_4 \cdot 5H_2O$) dissolved in 100 parts water are added and the mixture heated to 90-95° C. for four hours until the triazole formation is completed. 500 parts water are added and the reaction mixture cooled to 15-20° C., filtered and the product dried.

Example 4

- 70 The procedure of Example 3 is followed except that 17.8 parts of 2-(5-aminobenzotriazolyl)naphthalene-4,8-disulfonic acid is used in place of 14.5 parts of 2-(4'-sulfonylphenyl)-5-amino-2,1,3-benzotriazole.

7
Example 5The procedure of Example 3 is followed except that 13.8 parts of 2-(5-aminobenzotriazolyl)naphthalene-5-sulfonic acid is used in place of 14.5 parts of 2-(4'-sulfo-phenyl)-5-amino-2,1,3-benzotriazole.

8

The procedure of Example 4 is again repeated employing 15.5 parts of 4-amino-4'-chloro-2-stilbenesulfonic acid in lieu of the 13.8 parts of the stilbene compound described in Example 4.

Example 11

Example 6

The procedure of Example 1 is repeated employing in lieu of the 6.9 parts of 4-amino-2-stilbenesulfonic acid, 7.2 parts of 4-amino-4'-methyl-2-stilbenesulfonic acid.

The procedure of Example 4 is again repeated employing 15.5 parts of 4-amino-3'-chloro-2-stilbenesulfonic acid 25 as the stilbene moiety.

Example 7

The procedure of Example 2 is repeated employing 14.5 parts of the stilbene compound described in Example 6 in lieu of the 13.8 parts of that of Example 2.

35

Example 12

Example 8

45

The procedure of Example 3 is repeated employing 15.2 parts of 4-amino-4'-methoxy-2-stilbenesulfonic acid in place of the 13.8 parts of the stilbene compound of Example 3.

50

The procedure of Example 3 is repeated employing 15.2 parts of 2(N,N-dimethyl-sulfonamido)-4-aminostil-

Example 9

60

The procedure of Example 3 is again repeated employing 15.2 parts of 4-amino-2'-methoxy-2-stilbenesulfonic acid in lieu of the 13.8 parts of the stilbene compound of Example 3.

65

bene in lieu of the 13.8 parts of the stilbene compound of Example 3.

Example 10

9

Example 13

The procedure of Example 3 is repeated except that 18.5 parts of 2(N,N-bishydroxyethyl-sulfonamido)-4-aminostilbene is used in place of the 13.8 parts of the stilbene compound of Example 3.

Example 14

The procedure of Example 3 is again repeated using 18.5 parts of 2(N,N-diethyl-sulfonamido)-4-amino-4'-methoxystilbene in place of the 13.8 parts of the stilbene compound of Example 3.

Example A

The brightening agent of Example 1 is tested for brightness in accordance with the following procedure. To 100 parts of a water solution containing 0.00016 part of the bistriazole of Example 1 and 0.4 part of "Supersuds" there is added 5 parts of Indian Head cotton fabric in a launderometer. The fabric is maintained at 130° F. for 20 minutes in the dyebath. The cotton swatch is then given 2 rinses in lukewarm tap water and finally air dried at 55° C. The brightness of the resulting product is measured in an adapted fluorescent photometer and is found to give a brightness reading of 50.0 which value for the dye concentration herein used far exceeds the results obtained by other commercially acceptable brighteners. On visual comparison the product appears much whiter than the heretofore obtained fluorescent dyed products. A similar procedure is carried out except that the bistriazole concentration employed is 0.00032 part per 100 parts of solution. The brightness reading at this concentration is 66.8.

Example B

The bistriazole of Example 2 is tested for brightness in the same manner described above in Example A. The brightness readings obtained on the product dyed with a solution containing 0.00016 part of bistriazole per 100 parts of solution is 46.8. At twice this concentration, that is, 0.00032 part bistriazole per 100 parts of solution, the brightness reading is 63.3. This product is further tested for its chlorine stability in the following manner. 100 parts of a water solution containing 0.00032 part of bistriazole, 25 parts "Clorox" solution (15 parts "Clorox" containing 0.052 g. active chlorine per ml. in 1000 parts water), and 0.4 part "Supersuds" are heated to 130° F.

10

g. sodium m-bisulfite per 1. of solution) is added to destroy the "Clorox" and 5 parts Indian Head cotton fabric is added. The solution is then placed in a launderometer for 20 minutes at 130° F. The cotton swatch after rinsing twice in warm tap water and air drying at 55° C. has a brightness value of 73.4 in the adapted fluorescent photometer. It will thus be observed that the brightness of the resultant product actually has increased by about 13% above that obtained above in the absence of the "Clorox" solution. The procedure is again repeated except that the "Clorox" is destroyed after 20 minutes at the 130° F. temperature. The resultant cotton swatch

10

5

10

10

has a brightness value of 71.0 which is a 9% increase in brightness over the comparable sample dyed in the absence of the "Clorox."

Example C

25 The procedure of Example A is repeated employing three different concentrations of the bistriazole of Example 3. These concentrations are 0.00016 part, 0.00032 part, and 0.004 part in 100 parts of a water solution, each of the said solutions also containing 0.4 part of "Supersuds" as above described. The resultant cotton swatches after rinsing and drying had brightness values for the lowest concentration of dyestuff of 64.3, for the intermediate concentration 83.9, and for the highest concentration 148. Again these values far exceed any brightness values heretofore obtainable with other acceptable brighteners.

30 The chlorine stability of this product is tested in the manner similar to that described in Example B, the concentration of the dyestuff again being 0.00032. The brightness value obtained after the 5 minute "Clorox" treatment is 90.3, which represents an 8% increase in brightness as compared to the 83.9 value obtained at this concentration in the absence of the "Clorox." The brightness reading obtained after the 20 minute "Clorox" treatment is 92.3, which represents a 10% increase in brightness over the sample not subjected to the "Clorox" treatment.

35 The products of Examples 4 through 14 exhibit similar outstanding brightness values of "Clorox" stability and, 40 additionally, all of the products of Examples 1 through 14 exhibit excellent light-fastness characteristics.

45 Various other modifications and variations of this invention will be obvious and apparent to those skilled in the art and it is to be understood that such modifications and variations are to be included within the purview of this application and the spirit and scope of the appended claims.

We claim:

1. A compound having the formula:

2. A compound having the formula:

After 5 minutes sufficient sodium m-bisulfite solution (2.5

11

3. A compound having the formula:
